UNITED STATES PATENT OFFICE

2,108,148

METHOD OF MAKING HANDLED SHOPPING BAGS

Harford K. Steen, Newburgh, N. Y.

Original application December 5, 1935, Serial No. 52,955. Divided and this application November 2, 1936, Serial No. 108,824

5 Claims. (Cl. 93—35)

This invention relates to a method of making handled shopping bags, and has been divided from my application, Serial No. 52,955 filed December 5, 1935 for a Method of making shopping bags, and constitutes an improvement over U. S. Patent No. 1,799,072 issued to me on March 31, 1931 for a Method of manufacturing shopping bags.

In this invention, I provide a method whereby handles formed of cord or other material may be secured by an adhesive to the paper webs from which a bag is formed.

In place of the single web, a double web is used, i. e., two webs are fed through a suitable bag forming machine whereby the longitudinal edges of one web are secured to the longitudinal edges of the other web forming a bag tube. The handles in this case are secured, one upon each web, or both upon one web and so located that they nest with each other after the bag is formed and folded.

In this case, one of the webs may be wider than the other web and its gummed edges are folded over upon the edges of the narrower web, thus forming the seams on the edges of the bag.

The bag may also be made from two webs of equal width. The longitudinal edges of each are gummed and the webs folded and brought together to form a double spaced seam upon opposite sides of the folded bag, thus creating a band of double thickness upon each web and so located that, upon the webs being lapped over and secured together, the handles will be located between the double thickness, or within the lapped seam.

Or should two webs of different width be employed and the seams lapped to one side of the center, the handles may be attached by patches along the centerline of the bag.

In any of these types, the open end of the bag may be creased and turned in to form a double thick edge, either pasted down or left loose.

The object of the invention is to provide a process or method of manufacture whereby shopping bags may be fabricated from stock rolls of paper or the like, the material being fed from the rolls in the form of webs, which are formed with slits where the handles are to be located and in parallel relation to where the bag tube is to be severed from the web.

Another object of the invention is to provide a method whereby handles are formed from a roll of stock cord or suitable material, either of single or multiple ribbon twisted or braided and with or without a reinforcing wire, and, if desired, the

ends may be flattened or spread to give a greater surface for the adhesive, and placed upon patches provided with an adhesive and which also act as transfer means for conveying the handles to the webs and securing them thereto. Another object of the invention is to form the handles of different lengths and widths and so locate them, one upon each web so that when the bag is completed and folded, the two handles will nest one within the other to form a single thickness of handle when stacking the bags.

Another object of the invention is to provide a method whereby reinforcing patches can be formed from stock rolls of strip material either gummed or plain, and either moistened or gummed and adapted to receive and hold the formed handles in position during their transfer and adhesion to the web.

Another object of the invention is to provide a method whereby cord handles may be attached to webs during the fabrication of the webs into a tube before bottoming and not having to be attached to the finished bag after the same is completed.

Referring to the drawing:—

Figure 1 shows a bag fabricated from two webs of different widths, the wider web being creased and pasted to the narrow web to form the seams on the edges of the bag.

Figure 2 shows a bag fabricated from two webs of equal width and showing the lapped seams on the opposite sides of the bag, the handles being attached between the overlapping portions of the webs.

Figure 3 is a view of the open end of a bag made from two webs of equal widths having the two handles secured by patches to both webs.

Figure 4 shows the open end of a bag made from two webs of equal width having their edges overlapped and secured by each other to form the seams and the handles secured by patches upon these overlapped seams.

Figure 5 shows a schematic view illustrating the method employed in fabricating and attaching the handles to the styles of bags shown in the figures.

Figure 6 shows the end of a bag made from double overlapping webs, with the open end of the bag folded in.

In carrying out my invention, the mechanism required for the various steps and operations may be constructed in a single machine, or, as part of a bag making machine of the usual type, or, the bags may be taken from my apparatus when in the form of a tube and bottomed and folded

in another machine if desired, and in the description and illustrations of this present invention I have embodied my invention in a bag making machine without the bottoming and folding means.

5 Referring to the drawing:—

I have taken the usual bag making machinery and incorporated therein the required mechanism for making and attaching the handles and 10 severing the bag tube from the webs at the proper location to provide a bag length.

Referring to the form of bag shown in Figure 1: This bag comprises the wide web 10 and the narrow web 11. The wide web 10 is fed past the 15 double web seam paster 18 which applies paste to the two parallel edges of the web 10 which is then carried past the handle former and attacher 19 and over the relieved roller 22, or the edges of the narrower web may be pasted.

20 The narrow web 11 is carried past the second handle former and attacher 20 which secures the handle 16 to the center of the web, which is then carried over the relieved roller 21 and brought down in parallel and superimposed relation to the 25 web 10. The handles 16 are on the inner or adjacent surfaces of the webs 10 and 11 and in nesting registry with each other. The webs 10 and 11 are then brought together and passed through a former which folds over the pasted edges of the 30 wide web upon the edges of the narrow web to form a bag tube.

Now, referring to Figures 3, 4, and 6, where the bag is shown as composed of two webs 12 and 13 of equal width, having their edges folded and 35 pasted upon each other: One web is carried past the web seam paster 18 which applies paste along its two parallel edges and it is then carried past the handle former and attacher 19 which applies one handle 16 upon one of its pasted edges, and it 40 is then carried past the relieved roller 22.

The other web is treated in a similar manner, passing by a similar paste roller, the handle former and attacher 20 to the combiner where the webs are folded and combined together to form a 45 bag tube. In this case, it will be seen that the handles 16 are secured between the overlapping portions 14 and 15 of the webs, which thus supply reinforcement to the handles, or the handles may be attached with patches either between the overlapping portions of the webs or upon these overlapped portions within the bag, or adjacent thereto.

50 In both of these methods it will be noted that the handle and patch units are located in the center of the machine one above the other, thus doing away with the necessity of lateral adjustment for different widths of webs, as when a single web is used. The two handles are formed of different lengths and widths so that when at-

tached to the bag, the handles will nest one within the other when the finished bag is folded.

5 Of both of these styles shown in Figures 1 to 6, the open ends of the bags may be flanged if desired, or folded in 26.

Having thus described my invention, what I claim is new and desire to secure by Letters Patent, is:

1. A method of making handled shopping bags, which consists in causing bag making webs to travel in parallel relation, and applying an adhesive to one or more of the parallel edges of said webs for subsequently securing said webs together in the form of a tube, of forming cord handles of different widths and attaching the same to the 15 webs, tubing the webs and bottoming into a bag so that said handles will lie in a nested position, one within the other when the bag is folded.

2. A method of making handled shopping bags which consists in causing two webs of different 20 widths to travel through a bag making machine, and applying adhesive to the parallel edges of one of the webs, of forming handles of different widths and attaching said handles one to each of said webs in predetermined positions, combining 25 the two webs together in superimposed relation, and folding the edges of the wide web upon the edges of the narrower web to form a bag.

3. The herein described method of making handled shopping bags from two webs, which 30 consists in causing the webs to travel through a bag making machine and securing the same together to form a bag tube, forming handles of different widths and attaching said handles to said webs during their travel through said machine in such a manner that after the bag is folded, said handles will nest one within the other.

4. The method of making handled shopping bags from two webs of the same width, which 35 consists in applying an adhesive to one edge of each web in the form of a strip to provide for longitudinal seams, applying cord-handles to said coated strips, securing said webs together upon said handles to form a bag tube, and severing 45 said tube into bag lengths adjacent to said handles.

5. The herein described method of making handled shopping bags from two webs, which 50 consists in causing the webs to travel through a bag making machine, applying an adhesive in the form of a strip to one edge of each web to be used for forming overlapping seams, applying cord-handles of different widths to said adhesive strips at predetermined positions, forming said 55 webs into a bag tubing and severing said bag tube adjacent to said handles into bag lengths.

HARFORD K. STEEN.
